United States Patent Office

Des. 229,335
Patented Nov. 20, 1973

229,335

JEWELRY CLASP, OR SIMILAR ARTICLE

Lynn Steinman, Rye, N.Y. (6 Accessocraft Products Corp., 46-48 Lawton St., New Rochelle, N.Y.)

Filed Sept. 28, 1972, Ser. No. 293,125

Term of patent 14 years

Int. Cl. D11—01
U.S. Cl. D45—4 A

FIG. 1.

FIG. 2.

FIG. 3.

FIG. 1 is a top plan view of a jewelry clasp, or similar article showing my new design;

FIG. 2 is a top edge view thereof; and

FIG. 3 is a bottom plan view thereof.

I claim:

The ornamental design for a jewelry clasp, or similar article, as shown.
